PORTABLE VAPORIZED LIQUID FUEL COOKING STOVE

John F. Cross, Denver, Colo., assignor to United Bank of Denver National Association, Denver, Colo.

Filed Feb. 18, 1972, Ser. No. 227,700

Term of patent 14 years

Int. Cl. D7—02

U.S. Cl. D7—110

FIG. 1 is a top plan view of a portable vaporized liquid fuel cooking stove showing my new design.

FIG. 2 is an elevational side view of the fuel intake side of the stove, the view being partly in vertical section to show the shape of the housing adjacent the central opening in which the burner mechanism is located.

FIG. 3 is an elevational side view of one side of the stove, the opposite side being a mirror image of the one shown.

FIG. 4 is an elevational side view of the stove opposite the side shown in FIG. 2.

FIG. 5 is a bottom plan view of the stove.

I claim:

The ornamental design for a portable vaporized liquid fuel cooking stove, substantially as shown and described.
